CHARLES R. TAINTER, OF GUILFORD, CONNECTICUT.

PIPE-WRENCH.

1,328,744.

Specification of Letters Patent. Patented Jan. 20, 1920.

Application filed August 9, 1918. Serial No. 249,168.

To all whom it may concern:

Be it known that I, JOHN E. LENHOLT, a citizen of the United States, residing at Leete Island, in the county of New Haven and State of Connecticut, have invented a new and useful Pipe-Wrench, of which the following is a specification.

This invention has reference to pipe wrenches, and its object is to provide a pipe wrench, of the chain type, of particularly efficient construction and of few and simple parts not liable to get out of order, and in case of breakage, of easy repair.

In accordance with the invention there is provided a handle member terminating in a gripping end with a sloping series of teeth extending from one side of the handle member in a gentle curve toward the other side, meeting the line of the other side at an acute angle and constituting a jaw against which the pipe may be gripped by a length of chain fast at one end to the handle member close to the basic end of the jaw. The handle and toothed jaw may be made in one piece and on the side of the jaw toward the manipulating part of the handle there is provided a box or shell through which there is slidable a threaded shank having one end formed into a claw to be engaged by the chain. The threaded shank is provided with a nut or threaded sleeve whereby the effective length of the chain may be readily adjusted.

The invention will be best understood from a consideration of the following detailed description taken in connection with the accompanying drawing forming part of this specification, with the understanding, however, that the invention is not confined to any strict conformity with the showing of the drawing but may be changed and modified so long as such changes and modifications mark no material departure from the salient features of the invention as expressed in the appended claims.

In the drawing:—

Figure 1 is a side elevation of a chain wrench embodying the invention.

Fig. 2 is a front elevation of the structure shown in Fig. 1.

Fig. 3 is a section on the line 3—3 of Fig. 2.

Fig. 4 is a section on the line 4—4 of Fig. 3.

Fig. 5 is a fragmentary elevation of the

structure shown in Fig. 1, as viewed from the right, the chain being broken away on both sides of the claw.

Referring to the drawing, there is shown a handle member 1 with a manipulating end 2 of convenient shape for handling, which shape may follow the customary form of chain wrenches. At one end the handle member 1 is formed into a jaw 3, which jaw may be of generally rectangular shape in cross section and of somewhat greater width and thickness than the manipulating end 2. The extremity of the jaw 3 is provided with a curved series of gripping teeth 4, the curvature starting in the line of the length of the jaw at one face of the latter and proceeding in an arc struck from a center outside of the jaw 3 and ultimately merging into the other side or edge of the jaw at an acute angle thereto, the series of teeth being therefore convexly curved. The extremity of the jaw on the side remote from the teeth terminates in a short curved portion 5 meeting the toothed portion of the jaw in close relation to that edge of the jaw remote from the teeth. At the base of the tooth portion of the jaw the handle is provided with a recess or slot 6 traversed by a bolt 7 and entered by one end link of a chain 8, said chain being made up of alternating ring-shaped and flat links 9 and 10 respectively. It is to be understood, however, that while it is preferred to use a chain of alternating ring-shaped and flat links, this does not preclude the use of other types of chains. The form of chain shown in the drawing has been found particularly efficient in practice.

Secured to the handle 1 at that end of the jaw remote from the teeth 4 is a box or shell 11 fastened by rivets 12 or in any other suitable manner, or the box or shell may be actually or effectively integral with the handle as is the custom in the manufacture of wrenches of the type to which the invention belongs. Slidable lengthwise through the box or shell 11 and bearing against the corresponding edge or face of the head 3 is a shank 13 terminating at one end in an outstanding claw 14 and at the other end in a threaded continuation 15 to which latter there is applied a nut or threaded sleeve 16. The shank 13 may be of rectangular cross section so as to fit flat against the corresponding edge of the head 3 which is also made flat, thus preventing the claw shank, 110

and claw, from turning about its longitudinal axis. The claw 14 has closely adjacent jaws suitably shaped, as shown at 17 in Figs. 3, 4 and 5, to receive and hold links 5 of the chain 8 when placed between the jaws.

When it is desired to grip and turn a pipe, such as indicated at 18 in Figs. 1 to 4, the claw 14 is sufficiently loosened by unscrewing the nut or sleeve 16 and the toothed portion 4 of the jaw 3 is placed against one side of the pipe with the chain 8 about the pipe on the side thereof away from the toothed portion of the jaw and the chain is then carried over and against the end 5 of the jaw and a link is introduced into the claw 14, after which the chain is tightened to a suitable extent by suitably screwing up the nut or sleeve 16. Now, upon manipulating the handle end of the wrench in a 20 clockwise direction in the showing of Fig. 1, the jaw teeth 4 are caused to roll on the pipe tightening the latter against the chain 8 where embracing the pipe. The cam action on the pipe of the convexly curved 25 series of teeth in opposition to the holding action of the chain causes the teeth to bind tightly against the pipe and the latter is therefore turned in the desired direction, the grip of the wrench on the pipe increasing 30 with the force applied to the wrench.

It will be noted upon reference to Figs. 1 and 3 of the drawing, that one of the links is in contact with the end of the handle, said link riding over the curved portion 5. 35 This relieves the strain on the claws, it being shown in actual practice that by this arrangement, with the chain touching the end of the handle, the claws will stand greater strain without giving away, and the 40 tendency of the chain to slip on the pipe is avoided.

What is claimed is:—

1. A chain wrench comprising an elongated handle member formed at one end 45 with a toothed jaw having a curved series of teeth extending lengthwise of the handle member along one edge, a chain passed around and in contact with the end of the handle member, means for rigidly fastening one end of the chain to the handle member beyond the teeth, a longitudinally movable shank provided with an outstanding claw for engagement by the free end of the chain, means for slidably connecting the 50 shank and handle member together, and means for adjusting the shank and claw longitudinally on the handle member, the chain having one of its links in contact with the end of the handle when grasping 55 work.

2. A chain wrench comprising an elongated handle member formed at one end with a toothed jaw having a curved series of teeth extending lengthwise of the handle member along one edge, the opposite edge 65 meeting the teeth at the end of the handle member in a short curved portion, a chain passed around and in contact with the end of the handle member, and adapted to ride over the curved portion with one of its 70 links engaged with the end of the handle member, means for rigidly fastening one end of the chain to the handle member beyond the teeth, a longitudinally movable shank provided with means for detachably 75 engaging the free end of the chain, means for slidably connecting the shank and handle member together, and means for adjusting the shank longitudinally on the handle member.

3. A chain pipe wrench comprising a handle member terminating at one end in a toothed jaw provided with a convexly curved series of teeth extending lengthwise of the jaw from one edge thereof toward the other, 85 a box or shell on the handle member projecting from the side thereof remote from the toothed portion of the jaw, a claw having a shank extending through the box or shell and provided with a threaded portion 90 and a nut engaging the threaded portion, and a chain secured at one end to the jaw adjacent to the basic portion of the series of teeth and of a length to be passed about the jaw and engage the claw while encircling a pipe or the like engaged by the jaw. 95

4. A chain pipe wrench comprising a handle member with a jaw at one end, a chain secured at one end directly to the handle member adjacent to the jaw, and a claw 100 on the other side of the handle member for receiving and holding the other end portion of the chain, said chain comprising a series of alternate solid flat links and ring-shaped links, with the flat links arranged for 105 edge engagement with the work.

5. A chain pipe wrench comprising a handle with a fixed jaw at one end, a chain fast at one end to the handle in operative relation to the jaw, and a claw on the side of 110 the handle remote from the jaw to receive the chain, said chain being composed of a series of alternately arranged flat plate links and ring-shaped links, with the ring-shaped links connecting the plate links and holding 115 them in edge engagement with the work.

In testimony, that I claim the foregoing as my own, I have hereto affixed my signature.

JOHN E. LENHOLT.
